F. J. JOHNSON,
MEANS FOR LIFTING, LOWERING, AND SECURING A WINDOW SASH.
APPLICATION FILED JULY 2, 1919.

1,343,322.

Patented June 15, 1920.

UNITED STATES PATENT OFFICE.

FREDERICK J. JOHNSON, OF JERSEY CITY, NEW JERSEY.

MEANS FOR LIFTING, LOWERING, AND SECURING A WINDOW-SASH.

1,343,322.

Specification of Letters Patent. Patented June 15, 1920.

Application filed July 2, 1919. Serial No. 308,114.

To all whom it may concern:

Be it known that I, FREDERICK J. JOHNSON, a citizen of the United States, residing at Jersey City, county of Hudson, State of New Jersey, have invented certain new and useful Improvements in Means for Lifting, Lowering, and Securing a Window-Sash, of which the following is a specification.

My invention consists in a device attached to a window sash, by reason of which the sash may be lifted, lowered and secured in any desired position.

My invention is especially adapted for use in a window sash as commonly used in automobiles, although it may be used in any location.

The object of my invention is a device which is cheap in construction, will occupy little room, and will fully serve the purpose for which it is designed.

The accompanying drawing will serve to illustrate my invention, in which Figure 1 is a perspective view of a window jamb (in dotted lines), a window frame and sash, and the lifting, lowering and securing device with the sash shown in the half open position.

Fig. 2 is a vertical section through one of the frames, showing the lifting, lowering and securing device in elevation with the window sash in the open position.

Fig. 3 is a horizontal section on the line III—III of Fig. 1.

Fig. 4 is a vertical section on the line IV—IV of Fig. 2.

Fig. 5 is a detail view showing the position of the device when the sash is being raised.

Referring to the drawings; 5 indicates a window glass such as commonly used in automobiles. The glass is mounted in a channeled frame 6, the channel being closed at the bottom 7 to support the glass. The channeled frame 6 carrying the glass 5, is located, and adapted to move, in vertical channels 8 in the side frames 9. The side frames 9 may be formed of metal or wood, and are adapted to be attached to the window jamb 10 by screws 11. The side frames 9 have an inwardly projecting member 12, shaped to form the channels 8 on the inner surface. The projecting members 12 of frames 9 are cut away at 13, and in the side frames opposite to the part 13 cut away, are spaced recesses 14. 15 indicates a catch. This catch consists of two members 16—17.

The member 16 has formed on its inner end, an elongated rectangular block 18, which is secured to the frame 6 by the screws 19—20. The member 17 is pivoted to the member 16 at 21, and is shaped on its lower end to form a point 22, adapted to coact with the recesses 14 in the frame 9. Situated between the members 16—17, is a spring 23. The securing screw 20 projects outwardly from the block 18, so that when the members 16—17 are brought together, the end of the member 17 will bear upon the side of the screw 20 and thus prevent further compression of the spring 23. Instead of securing the member 16 to the frame 6 by screws, it may be secured in any other manner, as by electric welding. Instead of providing a separate screw 20, the block 18 may be shaped to provide a part against which the end 22 of the member 17 will coact when the members 16—17 are brought together.

The projecting members 12 of frames 9 are provided with vertical channels 24 in which a curtain 25, shown by dotted lines in Fig. 3, may have vertical movement. It will be seen that by placing the catches on the sides of the sash instead of in front, as is usually done, the curtain can be placed close to the sash.

The operation of my device will be readily understood. When it is desired to raise or lower the sash, the catches on each side are compressed. This releases the point 22 from the recesses 14 with which they are engaged, and the sash can be raised or lowered and secured in any position through the point 22 of the catch coöperating with any of the recesses 14.

Having thus described my invention, I claim:

1. A device of the character described, comprising a window frame having side frames provided with channels in their opposing faces in which a window sash may have vertical movement, also recesses in the rear of said side frames and slots in the front face of the side frames; catches for raising and lowering the sash, each catch consisting of two members, one member connected to the sash and the other member pivotally connected to the first member and adapted to co-act with one recess in the rear of the side frame.

2. A device of the character described, comprising a window frame having side frames provided with opposingly disposed

channels in which a window sash may have vertical movement, also recesses in the back of said side frames and slots in the front of the side frames; catches consisting of two members, one member connected to the sash and the other member pivoted to the first member and both members extending through the slot, the pivoted member adapted to co-act with one of the surfaces of the recess at the back of the side frame.

3. A device of the character described, comprising a window frame having side members, each side member provided with two vertical channels, one on the front of the frame and one on the rear; a slot located in the front of the front channel; a spring catch, consisting of two members, located in the said slot, one member connected to the sash and the other member pivoted to the first named member and adapted to co-act

with one surface of the rear channel in the side frame and a spring between said members.

4. A device of the character described, comprising a window frame in which a window sash may have vertical movement, handles secured to the sides of said sash and extending through slots in the frame to the front side thereof, levers pivoted to said handles in such a manner that they swing at right angles to the plane of the sash, one end of said levers extending outward under said handles and the inner end of said levers adapted to engage recesses formed in the back of said frame, and a spring located between said handles and the outer end of said lever, whereby the inner end of said lever is forced into engagement with said recesses.

In testimony whereof I affix my signature
FREDERICK J. JOHNSON.
